UNITED STATES PATENT OFFICE.

HENRY L. FERRIS, OF ALDEN, ILLINOIS.

HAY ELEVATOR AND CARRIER.

SPECIFICATION forming part of Letters Patent No. 276,016, dated April 17, 1883.

Application filed February 19, 1883. (No model.)

To all whom it may concern:

Be it known that I, HENRY L. FERRIS, a citizen of the United States, residing at Alden, in the county of McHenry and State of Illinois, have invented a new and useful Hay Elevator and Carrier, of which the following is a specification, reference being had to the accompanying drawings.

This invention relates to devices for elevating hay, straw, &c., and carrying it to the place at which it is to be deposited; and it consists in certain improvements in the construction and operation of the same.

In the drawings, Figure 1 is a perspective view of the apparatus in position. Fig. 2 is a vertical longitudinal sectional view of the same. Fig. 3 is a detail vertical sectional view illustrating the operation of the elevator and carrier car. Fig. 4 is a perspective view, in detail, of the same. Fig. 5 is a bottom detail view of the car. Fig. 6 is a detail end view of the same. Fig. 7 is a detail transverse sectional view thereof. Fig. 8 is a detail perspective view of the lower end of the pulley-block. Fig. 9 is a detail section through one end of the bail.

Referring to the drawings, A designates the frame of a barn or other structure in connection with which my invention is arranged to be used. In this frame is comprised a top beam, B, that provides a track on which the car C travels. This car consists of side plates, D D, having extensions E, projecting upwardly at the sides of the beam B, and carrying wheels or rollers F, that travel on top the said track B, and are formed with flanges G to prevent lateral displacement, and also a top plate, H, as shown. In constructing the car the side plates, D D, are bent or turned outwardly at the top of the car and at the commencement of the extensions E to form shoulders I I, on which the top plate, H, rests and is secured. At the bottom of the car, between the plates D D, are secured two blocks, J and K, respectively, both of which have their end faces, at the inner end, beveled, as shown at L. The block J is provided with a lug or projection, M, extending from its beveled edge into the opening or mouth N in the bottom of the car, between the blocks J and K. The sides D D, at the mouth N, are flared outwardly, as at O, to facilitate the passage of the eye of the elevating pulley-block hereinafter described. The

block K is formed with an interior concavity or recess, P, in which the end of the operating-cord Q is secured, from whence the said cord passes through a perforation, R, in the bottom of the concavity, around the pulley S in the elevating pulley-block T, up and over a pulley, U, journaled at the other end of the car C, between the plates, across to a pulley, V, in the frame A, and from thence down over suitable pulleys. A horse may be attached to the end of the said cord or rope Q; or it can be operated by hand-power or other means.

W is a trip-plate that is fulcrumed between the plates D by a cross-pin, X, and is formed with a curved recess or cut-away portion, Y, in its under edge, at one side of which is formed a curved hook, Z, that slides in a guide-groove, A², in the inner surface of the block K, this groove serving to obviate lateral strain on the said trip-plate. At the other side of the recess Y the end B² of the plate W is provided with a groove, C², to receive the projection M on the block J, and above this end B² with a shoulder, D², as shown. This trip-plate normally hangs with its recess Y just over the mouth N, and with its hook Z back from the mouth in the groove A². To the end of plate W having the curved hook Z is pivoted or hinged, as at E², an auxiliary plate, F², that normally projects up through and from a slot, G², in the top plate, H.

H² is a locking-lever plate that is fulcrumed between the plates D D by a cross-pin, I², at the end of the car opposite from the plate W, and has its top end, J², working in and projecting through a slot, K², in the top plate, H. This lever-plate is provided with a shoulder, L², facing the shoulder D² on the plate W, and hangs toward the center of the car by its own gravity.

M² is a plate secured to the under side of the beam B, at one end of the same, and provided with downwardly-extending flanges N² N²—one at each end—that are arranged to engage the plate F² and the end J² of the locking-plate H².

The pulley-block T is provided with a vertical extension, O², at its top, in which is formed an eye, P². At the bottom of the said block are provided a pair of ears, Q² Q², at each side. Between one of these pairs of ears is pivoted, by means of a cross-pin, R², the end of a bail,

S^2 , the free end of which is formed with a perforation, T^2 , through which passes a taper locking-pin, U^2 , that is also passed through perforations V^2 in the ears $Q^2 Q^2$. By removing the taper pin the bail can be swung on its pivot, so that the hay-fork can be placed therein, after which the bail is again locked in position by the pin.

The operation of my invention is as follows:

- 10 When the carriage or car C is at the end of the track having the plate M^2 the latter will be between the projecting end J^2 and the projecting plate F^2 , as shown in Fig. 3 of the drawings. The plates H^2 and W are then disengaged, and the pulley-block is lowered from the car to admit of attachment of the hay-fork. When the latter is secured on the bail of the block, with its load in place, the rope or cord Q is operated to elevate the pulley-block 15 with the hay-fork, the car being held from movement during this elevating movement by means of the flange N^2 engaging the projecting plate F^2 . As soon as the pulley-block is elevated to the car its eye P^2 enters the mouth of 20 the latter and passes into the recess Y of the trip-plate W . By this movement the said plate W is thrown up on its pivot until its hook Z abuts against the projection M , which draws the plate F^2 down, so that it does not project 25 above the top of the car, and the plate W is retained in this position by reason of its shoulder D^2 being engaged by and retained by the shoulder L^2 of the locking-plate H^2 . The pulley-block is now entirely supported, with its 30 load, by the projection M and the hook Z , and by drawing on the cord Q the car can be drawn along the track (the plate F^2 being down, so that it will not be engaged by the flange N^2) until the place of deposit is reached, when the 35 hay-fork can be tripped by any suitable mechanism to drop the load. As the car is returned back to the other end of the track the projecting end J^2 of the locking-lever plate H^2 strikes the flange N^2 of the plate M^2 , which 40 trips the said plate H^2 , so that the shoulders D^2 and L^2 are disengaged and the pulley-block is dropped from the car, ready for its next load as the plates H^2 and W resume their normal 45 position.

50 This invention will be found very convenient and efficient in operation, and its construction is simple, durable, and inexpensive.

I claim as my invention—

1. The combination, with the car having a 55 mouth or opening in its bottom and slots in its

top, and carrying two pivoted plates having shoulders on their adjoining edges, arranged to engage each other and arranged to normally project through the slots in the top, one of the said plates being provided with a hook 60 that is adapted to project across the mouth, of a pulley-block having a top eye adapted to engage the said hook, and mechanism for tripping and disengaging the said pivoted plates, as set forth.

2. The combination of the track-beam having an engaging-plate on its under side, the car suspended therefrom and arranged to travel thereon, said car being provided with a mouth or opening in its bottom and slots in its 70 top, a plate pivoted in the said car and formed with a shoulder in its inner edge, a hook-shaped extension adapted to project over the mouth or opening, and an auxiliary plate normally projecting through the top slot, another 75 pivoted plate having a shoulder and arranged to project through the other top slot, a pulley-block having an eye adapted to be engaged and held by the hook on the pivoted plate, and an operating-cord secured to one end of 80 the car and passing through the pulley-block, as set forth.

3. The combination of the track-beam having the plate M^2 at one end, on its under side, the car suspended from the track by extensions carrying rollers, and provided with the slots in its top and a mouth or opening in its bottom, from one side of which projects the extension M , the pivoted plate W , having the recess Y , curved hook Z , shoulder D^2 , and the 85 auxiliary plate F^2 , the lever-plate H^2 , having projecting end J^2 and the shoulder L^2 , a pulley-block having an eye at its top, and the operating-cord secured to the end of the car, passing under the pulley in the block and over a 90 pulley in the other end of the car, as set forth.

4. The combination, with the car having pivoted plates adapted to automatically engage and hold the pulley-block, of the pulley-block having an eye at its top, and having a 100 bail hinged to its bottom and arranged to have its free end secured between two ears on the block, as set forth.

In testimony that I claim the foregoing as my own I have hereto affixed my signature in 105 presence of two witnesses.

HENRY L. FERRIS.
